Fig. 1

Fig.3**Fig. 2****Fig.4**

FIG. 1 is a front elevational view of a piano case embodying my new design.

FIG. 2 is a side elevational view thereof.

FIG. 3 is a cross sectional view taken along the section line 3—3 of FIG. 2.

FIG. 4 is partial side elevational view with a part broken away, showing the music desk and its supporting means in cross section.

The stippled areas indicate areas of contrasting wood grain. The side of the piano case not shown is the same as the side shown. The dominant features of my design reside in the parts shown in solid lines. The conventional keyboard is fragmentarily shown by means of broken lines and is continuous across the piano as indicated by the dash-dot lines.

The top edge of the music desk is provided with a harmonizing curve, and each side edge of the music desk is vertical at the top and bottom with an inwardly curved portion extending therebetween.

I claim:

The ornamental design for a piano case, substantially as shown and described.
